United States Patent Office.

PETER H. NILES, OF BOSTON, MASSACHUSETTS.

Letters Patent No. 102,855, dated May 10, 1870.

IMPROVEMENT IN FUNNELS.

The Schedule referred to in these Letters Patent and making part of the same.

I, PETER H. NILES, of the city of Boston, in the county of Suffolk and State of Massachusetts, have invented certain Improvements in Tunnels, of which the following is a specification.

My invention relates to the combination of a tunnel, (constructed in the usual form,) a bent lever, hollow connecting-rod, and valve, for the purpose of opening and closing the orifice at the end of the tunnel, and allowing the air to escape.

The object of my invention is to facilitate the filling of vessels, and prevent any undue waste.

Figure 1 is a side elevation of a tunnel embodying my invention, and showing the orifice open.

Figure 2 is a vertical section of the same, showing the orifice closed.

A is the cone, and

B the tube forming a tunnel.

C is a lever, one end of which is bent so as to form a handle. This lever is attached to the rim of the tunnel.

The opposite end of the lever is attached to a hollow connecting-rod, D, which passes through the center of the tunnel vertically, and is provided with a valve, E, which coincides with the orifice at the end of the tunnel. The hollow connecting-rod forms an air-passage for the escape of air.

On the tube B is fitted an elastic, F, for the purpose of forming an air-tight joint between the tube and vessel.

The act of lifting the tunnel by the handle raises the opposite end of the lever, connecting-rod, and valve, closing the orifice, and retaining the surplus liquid. Releasing the handle allows that end of the lever to which are attached the connecting-rod and valve to fall, thereby opening the orifice, and allowing the liquid to escape.

Claim:

I claim—

A lever, one end of which is bent so as to form a handle, and is attached to the rim of a tunnel, in combination with a hollow connecting-rod and valve, and so arranged that the act of lifting the tunnel vertically by the handle causes the valve to rise, and by releasing the handle allows the valve to fall, as substantially described.

P. H. NILES.
